UNITED STATES PATENT OFFICE.

DARIUS E. SHRAUGER, OF ATLANTIC, IOWA.

METALLIC WINDOW FRAME AND SASH.

1,252,851.

Specification of Letters Patent.

Patented Jan. 8, 1918.

Application filed January 25, 1915. Serial No. 4,366.

To all whom it may concern:

Be it known that I, DARIUS E. SHRAUGER, a citizen of the United States, and resident of Atlantic, in the county of Cass and State 5 of Iowa, have invented a certain new and useful Metallic Window Frame and Sash, of which the following is a specification.

The object of my invention is to provide a metallic window frame of simple, durable 10 and inexpensive construction.

A further object is to provide a metallic window frame especially adapted for installation in the side wall of buildings, and so constructed and arranged as to permit the 15 ready insertion, removal, or replacing of a pane of glass.

Still a further object is to provide such a window frame so constructed and arranged that any water which may pass around the 20 glass will ultimately be discharged on the outside of the window.

Still a further object is to provide such a window frame and sash so constructed and arranged that the sash may be arranged for 25 vertical sliding or horizontal sliding, and in either case, any water passing around the glass pane will be discharged on the outside of the window.

A further object is to provide such a frame 30 so made, and so installed as to fit the wall snugly for making a tight joint.

My invention consists in the construction, arrangement and combination of the various parts of the device, whereby the objects contemplated are attained, as hereinafter more 35 fully set forth pointed out in my claims, and illustrated in the accompanying drawings, in which:

Figure 1 shows a front elevation of a window frame and sash embodying my invention.

Fig. 2 shows a horizontal sectional view of the same taken on the line 2-2 of Fig. 1.

Fig. 3 shows a vertical sectional view 45 taken on the line 3-3 of Fig. 1.

Fig. 4 shows a similar view to that shown in Fig. 3, on a similar scale with the sash removed, and

Fig. 5 shows a detail sectional view of a 50 portion of the upper part of the frame, showing the manner in which the edges of the frame are inclined in a direction to engage the wall.

In the exemplification of my invention 55 illustrated in the accompanying drawing, I have shown a window frame having the flat

side members 10, and the flat top and bottom members 11 and 12, forming a rectangular frame. In this connection it may be mentioned that when I refer to the top and 60 bottom members, I am speaking of a window in installation with the sash, which will be hereinafter described, and arranged to slide vertically. The frame and sash can be readily turned so that the sash may slide horizontally. The construction just mentioned, 65 is used for purposes of convenience.

Each member 10 and 11 has a portion 13 bent rearwardly in a horizontal plan, as illustrated in Figs. 2 and 3. At its rear edge, 70 the portion 13 of the top member 11 is bent upwardly at 14, so that the edges 11, 12 and 14 form an upwardly opening channel adapted to receive a board 15 for making a joint. The edges of the members 10, 11 and 12 and 75 the edge of the member 14 are slightly broken or bent at 16, and inasmuch as the material is somewhat resilient, these bent edges 16 snugly engage the wall.

The bottom member 13 is provided with 80 an upwardly bent bead or ridge 17, as shown, along a line spaced from its inner edge. The side members 13 are provided with similar vertical beads 18. The members 18 may be provided with suitable holes to receive pins 85 or nails 19, which serve as stops for holding the sash in raised position.

It will be seen from the foregoing description, that each side and top member of the frame is made from a single piece of metal 90 properly bent and folded.

My improved window sash comprises a top or horizontal member 20, which may be made of a single piece, as shown in Figs. 1 and 3, or may be folded for strength, as de- 95 sired.

The side members of the sash are each made of a single piece of metal, comprising the vertical flat portion 21, which is bent over toward the middle of the back part of 100 the portion 21, at 22 and 23. The members 22 and 23 have at their adjacent edges rearwardly parallel extensions 24, at the rear end of which are outwardly and inwardly extending flanges 25 and 26 respectively. 105

It will thus be seen that the portions 22, 24 and 25 form an outwardly opening vertical channel, and that the members 23, 24 and 26 form an inwardly opening channel.

The flanges 25 and 26 are soldered or 110 otherwise properly secured to the top member 20. In this connection attention is

called to the fact that the member 21 extends to position above the level of the upper edge of the flange 25, and below the lower edge of the flange 26. The importance of this construction will be hereinafter mentioned.

If it is desired to construct a window having two panes, of glass, a central vertical member may be employed, which is similar in construction to the side members with the exception that at the lower end, the central member is provided with a laterally extending member 27, which is adapted to be grasped for raising the sash. The bottom member of the sash is similar in construction, except that the parts are arranged horizontally instead of vertically.

The bottom frame member comprises the inward vertical member 28, a portion of which at the upper edge thereof, is bent over and extended downwardly to approximately the horizontal middle line of the portion 28, and is then inclined downwardly and outwardly at 29, then downwardly at 30. At 25 its lower edge, the member 28 is provided with an upwardly bent portion 31, at the upper end of which is an outwardly bent horizontal portion 32, at the upper edge of which is a downwardly extending portion, 30 inside of, but engaged by the portion 30. The portions 33, 32 and 31 form a downwardly opening channel, which receives the bead 17, of the lower frame member. The outwardly opening channels at the side of 35 the sash, receive the beads 18 and slide vertically thereon.

The glass panes 34 are inserted from above into the proper channels, as shown in Fig. 2. Where the frame and sash are installed in position for sliding the sash vertically, it will be seen that any water which may pass around the edges of the glass pane, will flow downwardly and toward the lower end of the window, and will pass outwardly 45 over the portion 29 to the outside of the window.

It will be seen that the portions 28, 29, and 30 of the lower sash member form a channel above and which receives the lower 50 channel formed by the portions 31, 32 and 33. The upper channel is connected with the lower channel, but the member 29 is inclined while the member 32 is horizontal, so that when the glass is installed the upper 55 channel may give somewhat to allow for expansion.

If the window frame is installed to per-

mit the sash to slide horizontally, it will be noted that the members 21 are longer than the combined length of the members 25 and 60 26, so that if water should collect back of the window-pane, it will flow out over the members 25 or 26 as the case may be to the outside of the window.

It will be seen that the pane of glass may 65 be readily and easily installed or removed.

One or more of the members 26 is provided with a tongue 35, which may be bent over the upper edge of the glass for holding it in position.

It will be understood that some changes may be made in the construction and arrangement of the various parts of the device, without departing from the essential features and purposes thereof, and it is my intent to cover by this application any such changes which may be included within the scope of my claims.

I claim as my invention:

1. In a window sash, a lower sash member 80 made of sheet metal, and having a lower downwardly opening channel with a member secured to the edge of one side of the channel and extending upwardly adjacent to the channel and beyond said channel, and 85 having at its upper end a downwardly extending portion having at its lower end a portion inclined downwardly and laterally above said lower channel, a portion at the end thereof extending downwardly on the 90 outer opposite side of said channel from said upwardly extending portion, whereby a second channel is formed above and receiving the first channel with the bottom member of the second channel inclined, so that 95 the resiliency of the metal may allow for expansion and contraction.

2. In a sash, a lower sash member, comprising a lower downwardly opening channel, and an upper and outer downwardly 100 opening channel receiving the first channel, resiliently connected therewith, and having its bottom member inclined from the lower channel upwardly and laterally for leaving a space between the bottoms of the channels, 105 whereby the resiliency of the metal will permit the expansion and contraction of a pane of glass received in said sash without breaking the glass.

Des Moines, Iowa, January 21, 1915.

DARIUS E. SHRAUGER.
